UNITED STATES PATENT OFFICE.

ALEXANDER WINTON, OF CLEVELAND, OHIO.

DESIGN FOR A FRAME FOR A STATIONARY EXPLOSION-ENGINE AND CONNECTED DYNAMO.

46,384.

Specification for Design.

Patented Sept. 8, 1914.

Application filed June 19, 1914. Serial No. 846,207. Term of patent 14 years.

To all whom it may concern:

Be it known that I, ALEXANDER WINTON, a citizen of the United States, residing at Cleveland, in the county of Cuyahoga and State of Ohio, have invented a new, original, and ornamental Design for Frames for Stationary Explosion-Engines and Connected Dynamos, of which the following is a specification, reference being had therein to the accompanying drawing.

This invention relates to improvements in designs for frames for stationary explosion engines and connected dynamos.

In the accompanying drawings: Figure 1

is a perspective view of one side of my improved design. Fig. 2 is a perspective view looking in the opposite direction and at the opposite side of Fig. 1.

I claim:

The ornamental design for a frame for a stationary explosion engine and connected dynamo, as shown.

In testimony whereof I hereunto affix my signature in the presence of two witnesses.

ALEXANDER WINTON.

Witnesses:

HAROLD B. ANDERSON,
W. A. WALKEMEYER.
